Primary Examiner — Karen E Eldridge Powers
(74) Attorney, Agent, or Firm — Leason Ellis LLP(57) **CLAIM**

The ornamental design for a tie and handkerchief retail combination, as shown and described.

DESCRIPTION

FIG. 1 is a front and side perspective view of a tie and handkerchief retail combination showing my new design;
 FIG. 2 is a front elevation view thereof;
 FIG. 3 is a rear elevation view thereof;
 FIG. 4 is a right side view thereof;
 FIG. 5 is a left side view thereof;
 FIG. 6 is a top plan view thereof; and,
 FIG. 7 is a bottom plan view thereof.
 The broken lines of FIGS. 1-7 are for illustrative purposes only and form no part of the claimed design.

1 Claim, 3 Drawing Sheets
